(57) CLAIM

The ornamental design for a clip, as shown and described.

DESCRIPTION

FIG. 1 is a perspective view of a clip showing our new design; FIG. 2 is a front view thereof, the back view being identical; FIG. 3 is a left side view thereof; FIG. 4 is a right side view thereof; FIG. 5 is a bottom view thereof; FIG. 6 is a top view thereof; FIG. 7 is a perspective view of a second embodiment thereof; FIG. 8 is a front view of FIG. 7, the back view being identical; FIG. 9 is a right side view of FIG. 7; FIG. 10 is a left side view of FIG. 7; FIG. 11 is a bottom view of FIG. 7; and, FIG. 12 is a top view of FIG. 7. The broken lines shown in the drawings are included for purposes of illustrating portions of the clip that form no part of the claimed design.
